UNITED STATES PATENT OFFICE.

ARTHUR M. ELLIOTT, OF OAKLAND, CALIFORNIA.

DESIGN FOR A TIRE TREAD.

Application filed February 9, 1922. Serial No. 617. Term of patent 3½ years.

To all whom it may concern:

Be it known that I, ARTHUR M. ELLIOTT, a citizen of the United States, residing at Oakland, in the county of Alameda and State of California, have invented a new, original, and ornamental Design for Tire Treads, of which the following is a specification, reference being had to the accompanying drawing, in which—

Figure 1 is a fragmentary plan view of a tire showing my new design.

Figure 2 is a cross section taken on line 2—2 of Figure 1.

I claim:

The ornamental design for a tire tread, as shown.

In testimony whereof I affix my signature.

ARTHUR M. ELLIOTT.
